UNITED STATES PATENT OFFICE.

JOHN W. WATSON, OF ROSEVILLE, ILLINOIS.

WIRE-TWISTING DEVICE.

1,125,417.

Specification of Letters Patent. Patented Jan. 19, 1915.

Application filed June 8, 1914. Serial No. 843,824.

To all whom it may concern:

Be it known that I, JOHN W. WATSON, a citizen of the United States, residing at Roseville, in the county of Warren and 5 State of Illinois, have invented a new and useful Wire-Twisting Device, of which the following is a specification.

The present invention appertains to wire twisting devices, and aims to provide a 10 novel and improved appliance of that character for use in constructing wire fences, for making splices, and the like.

The present invention contemplates the provision of a wire twisting device of 15 unique construction, whereby the device may be readily applied to and removed from a wire for twisting the terminal portion of the same or another wire therearound.

Another object of the present invention is 20 to provide in a wire twister, novel means for accommodating and holding the terminal portion which is to be wound or twisted around the wire over which the device is placed.

It is also within the scope of the present 25 invention to provide a wire twisting device of the character specified, which will be comparatively simple, non-encumbering, compact and inexpensive in construction, as well as being convenient, practical and efficient in its use.

With the foregoing and other objects in view which will appear as the description 30 proceeds, the invention resides in the combination and arrangement of parts and in the details of construction hereinafter described and claimed, it being understood that changes in the precise embodiment of the invention herein disclosed can be made 35 within the scope of what is claimed without departing from the spirit of the invention.

The invention has been illustrated in its preferred embodiment in the accompanying drawing wherein—

Figure 1 is an elevation of the device as applied to a wire. Fig. 2 is a longitudinal section of the device taken on the line 2—2 of Fig. 1. Fig. 3 is a cross section of the device taken on the line 3—3 of Fig. 2.

In carrying out the present invention, 50 there is provided a frame or body 1, preferably formed from a bar, having the parallel angular portions 2, through which is journaled for rotation, the tubular member or sleeve 3. The end portions of the tubular 55 member or sleeve 3 project beyond the angular end portions or bearings 2 of the frame or body, and the tubular portion or sleeve is also provided with a longitudinal slot 4 extending from end to end, and adapted to 60 register with slots or passages 5 provided in the portions or bearings 2 and opening at the free ends of the said portions 2.

As a means for rotating or actuating the sleeve 3, a bevel gear 6 is keyed or otherwise 65 secured upon the sleeve 3 adjacent the inner side of one portion 2, and has a radial slot or passage 7 registering with the slot 4 of the sleeve. The bevel gear 6 intermeshes with a bevel gear 8 keyed or otherwise se- 70 cured upon the inner end of a spindle or shaft 9 journaled through the intermediate or central portion of the body or frame 1. The outer extremity of the spindle 9 is squared, or formed, as at 10, for the engage- 75 ment of an ordinary crank brace (not shown), whereby the spindle 9 may be conveniently rotated to rotate the sleeve 9.

The sleeve 3 is provided with inner wire holding means, and to this end, a semi-tubular member 11 is fitted within the sleeve 3 opposite the slot 4, and is provided adjacent one end with a lug 12 engaging through an aperture 13 provided in the sleeve 3 dia- 80 metrically opposite the slot 4, to hold the 85 semi-tubular or channel member 11 against displacement within the sleeve 3 under ordinary conditions. The lug 12 and aperture 13 are preferably arranged adjacent the inner side of that portion or bearing 2 re- 90 mote from the bevel gear 6. The wire holding means also embodies a semi-tubular or channel member 14 coöperating with or complementing the member 11 to provide a complete tubular holding element. The mem- 95 ber 14 is insertible longitudinally into the sleeve 3 adjacent the slot 4, to close the said slot. The member 14 is provided at one end

with an outwardly projecting lug 15 adapted to enter one end of the slot 4 for holding the member 14 against lateral displacement, and to assist in applying and removing the 5 said member 14.

The protruding or end portions of the sleeve or tubular member 3 are provided with means for engaging the terminal portion of the wire which is to be twisted or 10 wound around the wire received by the holding means or tube 11—14. To this end, one end of the sleeve 3 is provided with an arcuate extension 16 diametrically opposite the slot 4, and having lugs 17 at its ends forming 15 hooks or seats 18. Secured upon the other protruding end of the sleeve 3 is a band or cuff 19 having a slot 20 registering with the slot 4 of the sleeve 3, and having an arcuate extension 21 projecting from the 20 end of the sleeve diametrically opposite the slot 4. The ends of the extension 21 are provided with lugs 22 forming hooks or seats 23, relatively larger than the hooks or seats 18 at the other end of the sleeve 3. 25 Thus, the hooks or seats 18 are adapted for engaging the smaller sizes or gages of wire, while the hooks or seats 23 are adapted for engaging the larger sizes or gages of wire, as will be obvious.

30 In use, when the twisting device is to be applied to a wire 24, as seen in Fig. 1, the retaining member 14 is withdrawn from the rotatable wire receiving sleeve 3, and the sleeve 3 is then rotated to bring its slot 4 into register with the slots 5 of the frame. Then, the sleeve 3 may be readily introduced over the wire 24, the wire passing through the slots 5 and 4 into the sleeve, whereby the member 11 will accommodate the wire. The 35 retaining member 14 is then slid longitudinally into the sleeve 3 to close the slot 4, and will mate with the companion element 11, to properly hold or accommodate the wire. The hooks or seats 18 and 23 are then 40 adapted to engage the terminal portion 25 of a wire or loop 26 which is to be wound about the wire or strand 24. As illustrated in Fig. 1, the terminal portion 25 is engaged by one of the hooks or seats 18, whereby 45 when the spindle 9 is rotated through the medium of a crank brace, or its equivalent, the sleeve 3 in being rotated, will carry the terminal portion 25 around the wire 24, to thereby wind or twist the portion 25 upon 50 the wire 24.

The opposite hooks or seats 18 and 23 of each pair, are adapted to engage the portions to be wound or twisted, when the sleeve 55 is rotated in either direction, and as above indicated, the hooks 18 are adapted to accommodate the smaller gages of wires, while the hooks 23 are adapted to accommodate the larger gages of wire. The device is readily applicable to the wire 24 at reversed

positions, to bring either hooks 18 or 23 into 65 action for winding the portion 25 as above described.

The present device may be employed for constructing wire fences, for splicing wires together, or for kindred or other purposes, 70 as will be obvious to those versed in the art. After the device has completed the winding operation, the same may be readily removed from the wire 24, by withdrawing the retaining member 14, and bringing the slot 4 of the sleeve 3 into registration with the slots 5 of the frame, in which event the device may be withdrawn from the wire 24. 75

Having thus described the invention, what 80 is claimed as new is:

1. In a wire twisting device, a rotatable sleeve adapted to receive a wire, and having an arcuate extension at one end, the extension having terminal lugs providing opposite seats for engaging a portion to be 85 wound around the said wire.

2. In a wire twisting device, a rotatable sleeve having a longitudinal slot for the passage of a wire therethrough, and a retaining element applicable to the sleeve for 90 closing the said slot.

3. In a wire twisting device, a rotatable sleeve having a longitudinal slot for the passage of a wire, and having means at one end for engaging a portion to be wound 95 upon the said wire, and a retaining element applicable to the said sleeve for closing said slot.

4. In a wire twisting device, a rotatable sleeve having a longitudinal slot for the 100 passage of a wire, and a retaining element insertible longitudinally into the said sleeve to close the said slot.

5. In a wire twisting device, a rotatable sleeve having a longitudinal slot for the 105 passage of a wire, and having means at one end to engage a portion to be wound upon the said wire, and a retaining element insertible longitudinally into the said sleeve for closing the slot. 110

6. In a wire twisting device, a rotatable sleeve having a longitudinal slot for the passage of a wire therethrough, a semi-tubular member disposed within the sleeve opposite the said slot, said member and sleeve having interengaging means to hold the said member against displacement, and a second semi-tubular member insertible into the sleeve to close the said slot and to complement the aforesaid member for holding 120 the wire.

7. In a wire twisting device, a rotatable sleeve having a longitudinal slot for the passage of a wire therethrough, and having an arcuate extension at one end opposite the 125 said slot, the ends of the extension having hooks to engage the smaller gages of wires, and a band secured upon the other end of

the sleeve and having a slot registering with the aforesaid slot, the band having an arcuate extension opposite the first-mentioned slot, the ends of the last-mentioned extension having hooks for engaging the larger gages of wires.

In testimony that I claim the foregoing as

my own, I have hereto affixed my signature in the presence of two witnesses.

JOHN W. WATSON.
